UNITED STATES PATENT OFFICE.

OTTAVIO ZANCAN, OF NEW YORK, N. Y.

TIRE CONSTRUCTION.

1,385,653.

Specification of Letters Patent. Patented July 26, 1921.

Application filed April 15, 1920. Serial No. 374,035.

To all whom it may concern:

Be it known that I, OTTAVIO ZANCAN, subject of the King of Italy, residing at New York, county of New York, State of New

5 York, have invented new and useful Improvements in Tire Constructions, of which the following is a specification.

This invention relates to improvements in tire construction, pertaining more particularly to structures employing the usual shoe or casing and an inner inflatable structure.

Various types of tire formations have been contemplated and employed, the form generally used being that of an outer shoe, 15 casing or tread structure of heavy material—generally fabricated—the casing being formed hollow to receive an inner tube, the walls of which are more or less flexible, the tube being inflated, the inflation serving to cause the walls of the tube to tightly contact the interior of the casing and the rim formation after the casing has been seated, inflation taking place after the casing has been properly positioned. This provides a 20 pneumatic support for the casing, serving to absorb the shocks, etc., present in service.

When the tube becomes leaky, as by puncturing, etc., removal is required and another substituted, and this requires, if substitution 30 is made while the wheel remains in position, that the vehicle be "jacked" up so as to remove the casing from off the ground, after which the holding ring is removed; the side of the shoe or casing drawn outward to 35 open the interior, the deflated tube removed, and the new tube—deflated—inserted in position, after which the reverse operation takes place. The operation is a slow and a 40 tedious one owing to the difficulties of properly positioning the inner tube and the casing, in addition to which the "jack" manipulation both before and after is required.

The present invention is designed to overcome some of these difficulties by changing 45 the form of the inner tube from that of an endless type to that of a closed type, in that the tube, while approaching the length of an endless tube, is less than such length, the ends being closed. The annular formation 50 is completed by a partition of resilient material, this material being arranged with recesses to receive and anchor the closed ends of the tube when the latter is inflated; since the partition is fixed in position, anchoring 55 of the ends of the tube serves to prevent

creeping of the latter, thus eliminating the possibility of placing a strain on the portion of the tube at the inflation nipple. The tube thus provides the pneumatic cushion for the casing with the exception of that portion which lies between the ends of the tube, and as this is relatively small as compared with the circumferential length of the casing, it does not materially affect the uniformity of support under service conditions, 60 the partition preferably having a formation which simulates the action of the pneumatic support in use. The major difference in result, however, is the presence of a portion of the casing support which need not be removed when substitution of one tube for another is required, this portion being sufficient to maintain the casing in proper position when the partition lies in the vertical 65 plane of the wheel axis and at the under side of the wheel. Hence, if the wheel be placed in this position there is no requirement for raising the casing from the ground. And this non-requirement of removal of the partition produces the result that it becomes unnecessary to release the casing at this point, 70 so that the rim itself may be carried up on the outer side of the wheel for some distance, thus providing a rigid support for the casing at this point, preventing liability of the 75 shoe working loose at the ends of the tube.

This permits the usual holding ring to be changed to a segmental element of a length to complete the ring with this fixed rim portion, it being possible to employ a cross-sectional form of segment to properly fit the casing, the incomplete ring being capable of ready positioning and securing in position; at the same time it can be removed bodily to expose a sufficient length of casing as to permit the substitution of the tubes without 80 affecting that portion of the casing which is being supported by the partition.

To these and other ends, therefore, the 85 nature of which will be readily understood as the invention is hereinafter disclosed, said invention consists in the improved construction and combination of parts, hereinafter fully described, illustrated in the accompanying drawings, and more particularly 90 pointed out in the appended claims.

In the accompanying drawings, in which similar reference characters indicate similar parts in each of the views,—

Figure 1 is a side elevation of a wheel 110

showing one embodiment of the present invention applied thereto.

Fig. 2 is a longitudinal section taken through the tube-anchoring partition.

Fig. 3 is an elevation of the retaining segment.

Fig. 4 is a sectional view taken on line 4—4 of Fig. 1, the view being on an enlarged scale and the shoe and inner tube being omitted.

Fig. 5 is a perspective view of a supporting member for the tube-anchoring partition.

Fig. 6 is a perspective view of a member employed in securing the partition in place.

In the drawing A indicates a wheel having a felly, a , this being of suitable form, the particular structure shown in the drawing being that of a detachable rim structure, the rim members a' and a'' being more or less of the usual type, these being held to position by the ring a^3 and clamps a^4 . Rim member a'' is slightly varied in the present construction.

10 10 indicates a shoe or casing of the usual type, this being secured in position between the fixed flange of rim member a'' and a two-part member of the opposite side, the part 11 being fixedly positioned—extending a certain angular distance of the circumferential length of the casing, the remainder of this distance being taken up by the member 11 a which is detachably secured in position by suitable means, such, for instance as lugs 35 11 b adapted to pass through openings in rim member a'' , as in Fig. 4.

The inner tube anchoring partition is indicated at 12 and shown somewhat in detail in Fig. 2, this being formed of resilient material in the main, and comprising a web portion 12 a extending somewhat radially and from which extend the anchoring portions 12 b these extending in opposite directions from web 12 a . As will be seen, the outer walls of the anchoring portions are comparatively thin, while the inner wall is provided with a bulging portion 12 c , giving to the recess or pocket which forms the anchor an enlarged mouth, a contracted throat 50 and an enlarged pocket formation beyond the throat, the end of the inner tube 13 being located in this enlarged pocket formation. When the tube is inserted—deflated—and then inflated, it will be readily seen that 55 bulge 12 c will act to prevent the tube reaching a diameter as great as that within the enlarged pocket, with the result that the tube end takes on the form of an enlarged head which is prevented from being drawn out of the pocket by the bulge 12 c . Since both ends of the tube are thus pocketed and anchored, the tube will be held against any tendency to creep.

60 The partition web may be solid or it may, as shown in the drawing, be provided with

an insertible member 12 d of suitable material.

The partition is secured in position by being secured to rim member a^2 , a member 14, shown in Fig. 5, having an inwardly-projecting portion 14 a adapted to extend into the partition in alignment with the web 12 a , said portion 14 a being formed with an opening to receive the projecting portion 15 a of a member 15 secured to the rim with portion 15 b extending through an opening in the rim. Member 14 is located between the partition and the rim, and the partition is secured in place by a suitable bolt 16 having its head located in a recess of the web 12 a and projecting through portion 15 a , the outer end receiving a nut. Obviously, this form of securing the parts in position is more or less illustrative.

Since the outer walls of the anchoring 85 pockets are relatively thin, it will be understood that if the tube becomes deflated under service conditions, there is less likelihood of the structure becoming damaged by the traveling on a "flat" tire; in addition, there is less liability to "bumping" under such conditions.

With the shoe or casing in position, it is necessary only to place the wheel in position where the web 12 a is at the bottom of the 95 wheel and in the vertical plane of the wheel axis, and remove member 11 a , this member having an angular length to overlap the mouths of both pockets. This permits the casing to be opened out sufficiently to remove the deflated tube and insert a new tube—in deflated condition—the ends of the tube being pushed into the pockets, the inflating tube being, of course, properly positioned. The casing is then restored, member 11 a returned to position and the tube inflated. During this operation, the casing is held in position by the fixed section 11, which also serves to strengthen the structure in the vicinity of the partition during 100 service.

While I have herein shown and described a preferred arrangement of parts, it will be readily understood that changes and modifications therein may be found desirable or 115 essential in meeting the exigencies of use, and I desire to be understood as reserving the right to make any and all such changes or modifications as may be found desirable or essential, in so far as the same may fall 120 within the spirit and scope of the invention as expressed in the accompanying claims, when broadly construed.

Having thus described my invention, what I claim as new is:

1. In tire construction, an annular shoe or casing, an inner inflatable tube having closed ends, a member for anchoring the tube ends, and detachable means for retaining the shoe or casing in position and adapt- 130

ed, when removed, to permit casing manipulation to substitute one tube for another.

2. In tire construction, an annular casing or shoe, an inner inflatable tube having 5 closed ends, a rim, and a member fixed to the rim for anchoring the ends of the inflated tube.

3. In tire construction, an annular casing or shoe, an inner inflatable tube having 10 closed ends, and a member for anchoring the tube ends, said member having a web portion and anchoring pockets on opposite sides of the web.

4. Tire construction of the type of claim 15 3 characterized in that the anchoring pockets have a configuration to form an anchoring pocket with a contracted throat leading thereto, whereby tube inflation will produce contracted tube portions spaced 20 from the tube ends.

5. An anchoring member for the ends of inner tubes comprising a member of resilient material having a web portion and hollow portions extending from such web portion 25 in opposite directions, said extended portions having external configurations to fit within the interior of a casing or shoe, the internal configurations of each hollow portion being adapted to produce a pocket

to receive and anchor the inflated and closed 30 end of a tube.

6. An anchoring member of the type of claim 5 characterized in that the internal configuration of each pocket includes a bulging portion spaced from the bottom of 35 the pocket and adapted to produce a contraction in the inflated end at a point spaced from such end.

7. An anchoring member of the type of claim 5 characterized in that the member includes means for securing it in fixed position relative to a rim, with the means located at the web portion of the member.

8. An anchoring member of the type of claim 5 characterized in that the member includes means for securing it in fixed position relative to a rim, said means including an element underlying the pocket-containing portions and having side flanges to support member portions.

In testimony whereof, I have signed my name to this specification in the presence of a subscribing witness, this 12th day of April 1920.

OTTAVIO ZANCAN.

Witness:

OSCAR CARLEBERG.
